CLAIM

The ornamental design for a paddle hanger, as shown and described.

DESCRIPTION

FIG. 1 is a front perspective view of an embodiment of the present invention holding a paddle.

FIG. 2 is a back perspective view of an embodiment of the present invention holding a paddle.

FIG. 3 is a front perspective view of an embodiment of the present invention.

FIG. 4 is a front view of an embodiment of the present invention.

FIG. 5 is a back view of an embodiment of the present invention.

FIG. 6 is a left side view of an embodiment of the present invention.

FIG. 7 is a right side view of an embodiment of the present invention.

FIG. 8 is a top view of an embodiment of the present invention; and,

FIG. 9 is a bottom view of an embodiment of the present invention.

The stippling on the straps in the drawings indicates a stretchy material.

The broken lines depict portions of the article and environment that form no part of the claimed design.

1 Claim, 6 Drawing Sheets
